UNITED STATES PATENT OFFICE.

RAIMUND GÜNTHER, OF VIENNA, AUSTRIA-HUNGARY.

TELEPHONIC APPARATUS.

SPECIFICATION forming part of Letters Patent No. 660,572, dated October 30, 1900.

Application filed November 18, 1898. Serial No. 696,820. (No model.)

To all whom it may concern:

Be it known that I, RAIMUND GÜNTHER, a subject of the Emperor of Austria-Hungary, residing at Vienna, in the Province of Lower Austria, in the Empire of Austria-Hungary, have invented certain new and useful Improvements in Telephonic Apparatus; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention has relation to telephony; and it has for its object the provision of means at a subscriber's station whereby a message or messages sent from any other station to said subscriber's station may, in the absence of the subscriber, be received and recorded for reproduction. To this end I provide at the subscriber's station an instrument capable of recording and reproducing a message or messages sent to said station during the absence 25 of the subscriber, as a graphophone or other like instrument, a motor for driving the recording-cylinder of said instrument, of any well-known construction, as a train of clock-gearing, an electrically controlled starting 30 and stopping device for said motor, an electromagnet for transmitting electric impulses corresponding to sound to the diaphragm of the graphophone which carries the recording-style, and a local shunt-circuit including the 35 said electromagnet and the electrical appliances controlling the starting and stopping devices for the graphophone-motor, and means for closing said shunt-circuit into the call and telephonic circuit and for cutting the call-bell and receiver out of the latter circuit; but 40 that my invention may be fully understood I will describe the same in detail, reference being had to the accompanying drawings, in which—

45 Figure 1 is a side elevation, Fig. 2 a plan view, and Fig. 3 an end elevation, of the starting and stopping mechanism of the graphophone-motor; and Fig. 4 is a diagrammatic view of so much of a telephone installation 50 as will be necessary to an understanding of my invention, showing at one station only a

spring-operated motor for actuating the phonogram-blank and the switch for directing current either to the telephone or the recording-circuit.

55 Referring to Fig. 4, S' and S² indicate the telephone instruments at two subscribers' stations; c', the main line connecting said stations; s, the switch at station S', controlling the call and telephone circuits; C and C', a local shunt-circuit adapted to be included in the call and telephone circuit through the switch s, said shunt-circuit including an electromagnet M, which operates the starting and stopping mechanism for the telephone-motor, 65 and an electromagnet N for transmitting telephonic impulses to the diaphragm that carries the recording-style of the phonograph.

70 Should it become necessary for the person at station S' to absent himself, he simply manipulates the switch s so as to cut the call and receiver circuits out of the main line and connect the shunt-circuit C C' with said main line, so that on calling the electromagnets M and N will be energized, the starting device 75 actuated, the motor U for the phonograph-cylinder started, and the phonograph placed in condition to receive and record the message transmitted. When this is done and station S' called off in the usual manner, the 80 electromagnets will be demagnetized and the motor for the graphophone-cylinder stopped, as hereinafter explained. On the return of the subscriber he can then switch the shunt-circuit out of the main line and switch the 85 call and receiver circuit back into said main line and have the recorded message reproduced in a well-known manner, the electromagnet N being of course first removed.

90 For starting and stopping the motor for the record-cylinder of the graphophone I provide a stop device normally in engagement with an operative element of the motor and a device for controlling the operation of said stop device.

95 As shown in the drawings, the stop device consists of a toothed wheel r, fast on an arbor d and normally engaging the fly W of a spring-actuated motor, and the device for controlling the operation of said toothed wheel r consists 100 of a ratchet-wheel R on said arbor d, having twice as many teeth as the wheel r. The

ratchet-wheel R is operated by a pawl-arm c^2 , pivoted to the free end b of an armature-lever a on an armature A and held in contact with the ratchet-wheel R by a spring F, and M is 5 the electromagnet, whose poles are extended toward each other with a view to increasing the magnetic field.

It will readily be understood that when the electromagnet M is energized and the armature A is attracted the pawl-arm c will cause the wheels R and r to revolve a distance equal to that between two teeth on wheel R; but inasmuch as the wheel r has only half as many teeth as the wheel R and in view of the 15 fact that the arrangement of the teeth on both wheels is such that those on wheel R lead or are in advance of the teeth on wheel r the fly W will be released and the motor started. When, on the contrary, the electromagnet M is demagnetized, the armature A and its lever a will be retracted by a spring f, the pawl-arm c^2 riding back on wheel R to engage the next tooth thereon, so that when the electromagnet is again energized and demagnetized by the closure and subsequent 20 interruption of the main-line circuit in calling off as usual said armature-lever will first be attracted, thereby imparting another partial revolution to wheels R and r , whereby a tooth 25 of the latter is moved into the path of the fly W and the motor stopped, the armature-lever being next retracted to a position to again impart a partial rotation to wheels R and r , and thereby release the fly W on the next closure 30 of the main-line circuit.

As is the practice in telephones, I may arrange a metallic diaphragm B in front of the pole of the electromagnet N and connect said diaphragm with the diaphragm D that carries 40 the phonograph-style, and thus transmit the current impulses to the last-named diaphragm, which will be of advantage in long-distance telephones where direct transmission becomes more or less difficult, and the weakening 45 of the vibrations of the diaphragm resulting from this arrangement may be avoided by the interposition of a sound-strengthener of any well-known description, as is the common practice.

50 As the phonograph and its spring-actuated motor may be of any well-known or usual con-

struction I have deemed it unnecessary to illustrate the same.

I am aware that phonographs have before my invention been used to record telephone-messages either at one or both ends of the line for the purpose of obtaining automatically a record of the messages transmitted. My invention, however, does not lie broadly in means for obtaining a phonographic record 55 of telephone-messages, but in the means for obtaining a record of such messages automatically without the intervention of a person at the receiving-station or, in other words, during the absence of an attendant at the receiving-station.

Having thus described my invention, what I claim as new therein, and desire to secure by Letters Patent, is—

1. In a telephone-circuit, the combination 70 with the receiver, transmitter and signaling device, of an auxiliary circuit, a switch for connecting the auxiliary circuit to line and simultaneously disconnecting the subscriber's station and signaling device, electromagnetic 75 devices in parallel in said auxiliary circuit, one of said devices arranged to operate a phonographic recorder and the other organized to set in motion means for driving the phonogram-blank, substantially as and for 80 the purpose set forth.

2. In a telephone-circuit, the combination 85 with the receiver, transmitter and signaling device; of an auxiliary circuit, a switch for connecting the auxiliary circuit to line and simultaneously disconnecting the subscriber's station and signaling device, electromagnetic 90 devices in parallel in said auxiliary circuit, one of said devices arranged to operate a phonographic recorder and the other organized 95 to operate an armature for setting in motion and stopping a suitable motor for driving the phonogram-blank, said device responding only to signal-current impulses, substantially as and for the purpose set forth.

In testimony that I claim the foregoing as my invention I have signed my name in presence of two subscribing witnesses.

RAIMUND GÜNTHER.
